UNITED STATES PATENT OFFICE.

MANSFIELD C. CRAWLEY, OF GROTON, NEW YORK, ASSIGNOR TO ADDOGRAPH COMPANY, OF LOS ANGELES, CALIFORNIA, A CORPORATION OF CALIFORNIA.

TYPEWRITING MACHINE.

Application filed August 29, 1917, Serial No. 188,771. Renewed April 16, 1923.

To all whom it may concern:

Be it known that I, MANSFIELD C. CRAWLEY, a citizen of the United States, and a resident of Groton, in the county of Tompkins and State of New York, have invented certain new and useful Improvements in Typewriting Machines, of which the following is a specification.

This invention relates particularly to improvements in means for vertically shifting the platen to provide for printing the several case characters.

In the typewriting machine shown in Patent No. 1,156,061, dated October 12, 1915, the type bars are moved to printing position by means of an intermittently operating motor, preferably a spring, and the said intermittent motor is withdrawn or retracted by means of a continuously operating motor, the connection between this latter motor and the motor for operating the type bars being controlled by suitable keys arranged in the keyboard. The platen shifting mechanism described herein is well adapted for use in that type of machine, but, of course, it is not restricted in its application and may be applied to any power-actuated typewriting machine having a suitable operating motor.

One of the principal objects of the invention is to provide a case shifting mechanism normally disconnected from the power means and adapted to be connected to said power means by key-controlled mechanism for a period of time sufficient to effect the change of case irrespective of the time of release of the key of said key-controlled mechanism.

Another object of the invention is to provide power-actuated means for vertically shifting the platen shift frame or other case-shift support and for locking it in position for the upper case characters by the action of gravity, and to provide key-controlled means for releasing the platen from its upper case position.

Another important object of the invention is to provide a continuously operating shaft and key-controlled mechanism adapted to be connected to said shaft for moving the platen shift frame or other case-shift support to its upper case position, said means being then automatically disconnected from the shaft and the platen shift frame or other case-shift support locked in its raised position;

tion; and a further object of the invention is to provide an additional key-operated means for releasing the platen shift frame or other case-shift support from its upper case position and permitting it to move downwardly to its normal or lower case position.

Another object of the invention is to provide a continuously operating shaft and key-controlled means adapted to be connected to said shaft for shifting a platen shift frame or other case-shift support to its upper-case position and locking it in said position after release of the key controlling said means, and to provide an additional key-controlled means for releasing the shift frame or support from its upper-case position and permitting it to move downwardly to its normal lower-case position only upon release of the key controlling said additional means following a depression of said key.

A further object of the invention is to provide a key-controlled power-actuated case-shift mechanism wherein a shift-frame is locked in upper case position and is both shifted to upper case position and released by power other than that applied by an operator.

There are other important objects and advantages of the invention, all of which will appear hereinafter, and it will of course be understood that this invention is not confined to that type of case-shift mechanism in which the shift-frame or support carries the platen and is shifted relatively to the type-bars to change case, since it is adapted for use in the equivalent type of case-shift mechanism in which the shift-frame or support carries the type-bars and is shifted relatively to the platen to change case.

In the drawings, Figure 1 is a vertical longitudinal sectional view of a portion of a typewriting machine, showing the invention applied thereto;

Fig. 2 a transverse vertical sectional view of the machine, showing the platen shifting mechanism;

Fig. 3 a view similar to Fig. 1, showing the platen shifted to the upper-case position;

Fig. 4 a detail plan view of the dog which connects the case shift means to the drive shaft; and

Fig. 5 a detail view showing the position of the parts at the completion of the case shift movement.

The case-shift mechanism herein shown and described possesses certain features in common with the case-shift mechanism forming the subject matter of my Patent No. 1,455,109, dated May 15, 1923. The broad claims to subject matter common to said 10 patent and this application are made in said patent, the present application being subordinate to said patent wherein is shown a case-shift mechanism in which a case-shift support is moved by power taken from a 15 constantly running shaft, the case-shift mechanism embodying a shift and lock-up control key and a temporary shift control key which is operable also as a release key for effecting restoration of the parts to normal after an operation of the shift and lock-up key.

Referring to the various parts by numerals, 1 designates the drive shaft which is continuously operated by means of a suitable 20 motor (not shown) connected by a belt or other suitable means to the drive pulley 2 mounted on said shaft. Rigidly secured on the shaft 1 is a worm 3. In the upper portion of the typewriter frame is mounted the 25 platen 4, said platen being suitably supported for a vertical movement. Mounted in the platen carriage and adapted to move transversely of the machine with the platen, as the platen is moved for letter or word 30 spacing, is a track or bar 5, said bar forming a part of a suitable shift frame in which the platen is mounted. It is to be understood that this shift frame may be of any suitable construction.

In the lower part of the machine frame, directly below the bar 5 of the platen shift frame, is mounted a transverse rock shaft 6, the ends of said shaft being suitably journaled in the frame of the machine. The 40 said shaft 6 is formed with a short crank portion 7 on which is journaled a vertically extending shift bar 8 in the upper end of which is mounted a roller 9 which at all times engages the under side of the shift bar 5. In the normal position of the platen the crank portion 7 of shaft 6 extends downwardly so that the platen is maintained in position for printing lower-case characters. In order to lift the platen into its upper-case position the shaft 6 is partially rotated. On the shaft 6 is rigidly secured a pinion 10, and meshing with said pinion is a segmental rack 11 mounted on the forward end of a pivoted arm 12, said arm being adapted to 50 be vertically reciprocated through power-actuated mechanism put into action by suitably disposed keys, as will be fully herein-after described.

Mounted in the machine frame is a transversely extending rock shaft 13, the ends of

which are journaled in suitable bearings. Rigidly secured to said shaft at each end thereof is a forwardly extending arm 14. A spring 14^a is connected to each of said arms and to the base of the machine, to return said arms and the shaft 13 to their normal down positions. The forward end of one of said arms 14 is adapted to be engaged by the rear end of a shift lever 15, the rear end of the other arm 14 being adapted to be engaged by the rear end of another shift lever 15^a. As shown in the drawings the shift lever 15 is arranged at the left-hand side of the machine and the shift lever 15^a is arranged at the right-hand side thereof. By depressing the finger key 16 of either one of said shift levers, the cooperating arm 14 will be lifted and the shaft 13 rocked. Secured rigidly to the rock shaft 13 is a forwardly extending arm 13^a, the forward end of which is connected to an upwardly extending dog-operating bar 17 whose upper end is adapted to engage a dog and to move it into engagement with the worm on the operating shaft, all of which will more fully 85 hereinafter appear.

Pivotedly mounted upon a suitable support within the machine frame is a bell-crank lever 18, one arm of which extends upwardly and is pivotally connected to a horizontal dog 19; the other arm of said lever extending substantially horizontally and being pivotally connected to a depending rack-operating link 20. The lower end of this link is formed with a slot 21 in which fits a pin 22 rigidly secured to the rack arm 12. In the normal position of the link 20 the pin 22 engages the upper wall of the slot 21, the said slot extending downwardly from said pin, as shown clearly in Fig. 1, so that upon moving the link 20 downwardly the arm 12 and its rack 11 are correspondingly moved. The free end of the dog 19 is formed with an upwardly extending lug 23 which is adapted to be brought into engagement with the worm 3. The said dog 19 is also formed with a laterally extending lug 24 which is adapted to be engaged by the notched upper end of the dog-operating bar 17, said bar being adapted to move the dog upwardly to bring the lug 23 into engagement with the worm. Directly below the worm is rigidly mounted a guide plate 25 formed with a stop 26 at its outer end. This plate is provided with a slot 27 adjacent the stop 26, through which slot the lateral finger 28 of the dog 19 is adapted to pass. In the normal position of the dog 19 the finger 28 is in engagement with the stop 26. Upon lifting the bar 17 the finger 28 passes upwardly through the slot 27 and the lug 23 is brought into engagement with the worm 3. The rotation of the worm carries the dog laterally toward the right, as 120

viewed in Fig. 2, the finger 28 riding over the guide plate 25 until it reaches the inner edge thereof, whereupon said finger drops from the plate and the dog is released from the worm. A spring 29 restores the bell-crank lever 18 to its normal position and at the same time returns the dog 19 to the position shown in Fig. 2, wherein the finger 28 is in engagement with the stop 26 and is directly below the slot 27. Spring 30 withdraws the dog from the worm 3 when the finger 28 is released from the plate 25, and lowers said dog sufficiently to permit said finger to travel under the plate 25 until it reaches the stop 26. Suitable stop pins 31 and 32 are provided for the bell-crank lever 18 and the dog 19, stop 32 being carried by the said lever. The bar 17 may be suitably guided in its vertical movement, and a spring 17^a holds it yieldingly in position to engage the dog 19.

When the dog 19 is moved toward the right through its engagement with the worm 3 the bell-crank lever is swung on its pivot 26 and the link 20 is depressed or moved downwardly. Because of the connection between the link 20 and the pivoted rack arm 12 the said arm is moved downwardly and the rack 11 rotates the shaft 6 over rearwardly because of its geared connection with the pinion 10. The rotation of the shaft 6 moves the crank 7 into its upper position thereby vertically shifting the bar 8 and lifting the platen into its upper case position. The shaft 6 is provided, near the left-hand end thereof, with a stop pin 33 which is adapted to engage a fixed pin 34 mounted in the machine frame. These two pins are arranged to engage each other when the shaft 6 has been given slightly more than a one-half revolution over rearwardly, so that pin 33 will have moved slightly beyond the vertical center of the shaft when it is at rest against the pin 34, and the weight of the platen sustained through the bar 8 and roller 9 will hold said shaft locked in its partially rotated position. By this means the platen will be locked in its upper-case position.

Rigidly secured to the shaft 6 near the right-hand end thereof is a radial release pin 35. In the normal position of said shaft, when the platen is in position for printing lower-case characters, the release pin extends rearwardly, as shown in full lines in Fig. 1. When the shaft 6 is rotated over rearwardly to place the platen in its upper-case position the release pin is moved to the position indicated in Fig. 3, the said pin in this position extending forwardly. Pivottally mounted on the shift lever 15^a is an upwardly extending release hook 36. The lower end of this hook is adapted to abut squarely against a transverse release bar 37 when the shift lever

is in its lower normal position, as indicated in Fig. 1. Connected to the release hook and to the shift lever is a spring 38, said spring tending to throw the release hook rearwardly; and to limit the rearward movement of the release hook when free from the release bar 37 is a pin 39 mounted on the shift lever 15^a.

When the platen has been raised to its upper-case position through the means controlled by the shift key 15, the pin 33, as stated hereinbefore, engages the stop pin 34 and the platen is locked in its upper position. When it is desired to return the platen to its lower-case position shift lever 15^a is operated. As the rear end of the said lever is lifted free of the release bar 37 the release hook 36 will be drawn rearwardly by its spring into position to engage the end of the pin 35. Upon the release of the shift lever 15^a the springs 14^a attached to the arms 14 return the shift lever to its normal position thereby sufficiently rotating the shaft 6 over forwardly through the release pin 35 and hook 36 to carry the crank 7 back again beyond its dead center, whereby the weight of the platen will then complete the return of the shaft and the connected segment 11 to their normal positions. When the squared lower end of the release hook engages the release bar 37, said hook is thrown forwardly out of the path of the pin 35.

When it is desired to move the platen into its upper-case position and to let it remain there without manual effort in order that a number of upper-case characters may be written, the shift lever 15 at the left-hand side of the machine is operated. When, however, it is desired to hold the platen in its upper-case position merely temporarily while writing a capital letter or the like, the shift lever 15^a at the right-hand side of the machine is operated. It is to be understood that the release hook 36 is secured to the shift lever 15^a and not to the shift lever 15.

The slot 21 in the link 20 is to permit the link 20 and bell-crank lever 18 to return to their normal positions with the platen locked in its upper-case position. It will, of course, be understood that in this position the rack 11 is in its lower position, the slot 21 being necessary in order to permit the link 20, to have an upward movement independently of the segment-carrying arm 12.

From the foregoing it is manifest that the operation of either one of the shift levers will move the dog 19 into engagement with the worm 3 and that thereafter the power-actuated means will shift the platen to its upper case position. It is also clear that to release the platen from its upper-case position it is only necessary to operate shift lever 15^a and then release it. These operations require very little effort on the part of the operator. The power-actuated means per-

forms all of the work of lifting the platen to its upper-case position, the key-operated means merely connecting the power or motor to the platen shifting means.

- 5 The mechanism interposed between the drive shaft and the shiftable platen support constitutes a case shift mechanism by means of which the platen is moved to its upper case position. When the platen is locked in 10 its upper case position, that portion of the case shift mechanism which is directly connected to the platen support, is also locked. That portion of the case shift mechanism which is adapted to be directly engaged with 15 the drive shaft is released from the drive shaft at the completion of the case shift movement, and automatically returns to its normal position. The case shift mechanism, however, as a whole, remains inoperative so 20 long as the platen support and that portion of the case shift mechanism directly connected thereto, is locked in the upper case position; although there would be an idle movement of a part of the case shift mechanism 25 upon the operation of either one of the shift keys.

What I claim is:—

1. In a typewriting machine, a constantly rotating power-driven shaft, a support movable to change case, mechanism for shifting said support and locking it in upper case position, means for connecting said support-shifting mechanism with said shaft, a pair 30 of shift-controlling key levers each operable 35 without moving the other to actuate said connecting means, and means whereby the support-shifting mechanism will be returned to normal position upon release of the key of one only of said levers, whereby 40 the support always will remain in upper case position after depression and release of the key of the other lever and may return to normal position either after depression and release of the first key lever following an 45 operation of said other lever or after release of the first key lever following a case-shift movement of the support effected by a depression of the key of said first key lever.

2. A typewriting machine comprising a 50 constantly operating drive shaft, a case-shift-support, means adapted to be operated through said drive shaft for shifting the case-shift-support to its upper-case position, key-actuated means for connecting said 55 shifting means to the drive shaft, and means for automatically disconnecting said shifting means from said shaft after the shifting action is completed.

3. A typewriting machine comprising a 60 support movable to change case, power means for moving said support to upper case position, a pair of shift controlling keys, means whereby upon depression of either key said power means will move the 65 support to upper case position, means

whereby said support will be held in upper case position after release of one of the keys and will return to normal position only after release of the other key following a depression of said other key to cause a case-shift 70 operation or after release of said other key following a depression thereof after a case-shift operation effected by the first key.

4. A typewriting machine comprising a support movable to change case, power 75 means for moving said support to upper case position, a pair of shift controlling keys, means whereby upon depression of either key said power means will move the support to upper case position, means whereby said support will be held in upper case 80 position after release of one of the keys, and means effective only on the up or release stroke of the other key following a depression thereof for returning the support to 85 normal case position.

5. A typewriting machine comprising a constantly operating drive shaft, a case shift mechanism adapted to be operated through said shaft, two shift keys each adapted to 90 independently connect the case shift means to the drive shaft, means to lock the case shift mechanism in its upper case position, and means rendered effective by depression of one shift key to release said lock and permit the case shift mechanism to return to 95 its normal position only when the said shift key is released.

6. A typewriting machine comprising a constantly operating drive shaft, case shift mechanism adapted to be operated through said shaft but normally disconnected therefrom, two shift keys one of said keys actuating means to connect the case shift mechanism to the drive shaft, means to automatically effect locking of the case shift mechanism in its upper case position, and spring means rendered effective by operation of the other shift key to release said case-shift mechanism and permit the case shift mechanism to return to its normal position.

7. In a typewriting machine, the combination of a support shiftable to change case, power-driven means for shifting the support to upper case position, a key operatively connected to put said power-driven means into action when depressed, and means for effecting restoration of the support to normal including a spring in which power for effecting said restoration is stored by force applied by an operator to the key in depressing the key.

8. In a typewriting machine, the combination of a constantly rotating shaft, a support shiftable to change case, power-driven mechanism for shifting said support to upper case position and holding it there, means for connecting said mechanism with the shaft, a pair of shift keys for actuating said means to connect said mechanism with

the shaft upon depression of either key, means controlled by one key only for connecting said key with said mechanism, and a spring tensioned by depression of the last mentioned key and effective through said key and the means controlled thereby on said support-shifting mechanism to release the support and permit it to return to lower case position.

5 adapted to be moved by said worm, means adapted to be operated by said dog for shifting the platen to its upper-case position, two shift keys, means operated by said shift keys to move the dog into engagement with 70 the worm to shift the platen to its upper-case position, means to automatically lock the platen in said position, and means operated by one of said shift keys upon the release of said key to release the platen from its upper-case position.

10 9. A typewriting machine comprising a constantly operating drive shaft, a worm thereon, a platen, means adapted to be operated through said worm for shifting the platen to its upper-case position, and key-actuated means for connecting said platen shifting means to said worm.

15 10. A typewriting machine comprising a constantly operating drive shaft, a worm thereon, a platen, means adapted to be operated through said worm for shifting the platen to its upper-case position, key-actuated means for connecting said platen shifting means to said worm, and means for automatically disconnecting the platen shifting 25 means from said worm.

30 11. A typewriting machine comprising a drive shaft, a worm thereon, a platen, a dog adapted to be moved by said worm, a key, key-actuated means for moving said dog into engagement with said worm, and means adapted to be operated by said dog for shifting the platen to its upper-case position.

35 12. A typewriting machine comprising a drive shaft, a worm thereon, a platen, a dog adapted to be moved by said worm, a key, key-actuated means for moving said dog into engagement with said worm, means adapted to be operated by said dog for shifting the platen to its upper-case position, and means for locking the platen in its upper-case position.

40 13. A typewriting machine comprising a drive shaft, a worm thereon, a platen, a dog adapted to be moved by said worm, a key, key-actuated means for moving said dog into engagement with said worm, means adapted to be operated by said dog for shifting the platen to its upper-case position, means for locking the platen in its upper-case position, and key-actuated means for releasing the platen from its upper-case position.

45 14. A typewriting machine comprising a drive shaft, a worm thereon, a platen, a dog adapted to be moved by said worm, a key, key-actuated means for moving said dog into engagement with said worm, means adapted to be operated by said dog for shifting the platen to its upper-case position, and means operated by said key for releasing the platen from its upper-case position upon the release of said key.

50 15. A typewriting machine comprising a drive shaft, a worm thereon, a platen, a dog

adapted to be moved by said worm, means adapted to be operated by said dog for shifting the platen to its upper-case position, two shift keys, means operated by said shift keys to move the dog into engagement with 70 the worm to shift the platen to its upper-case position, means to automatically lock the platen in said position, and means operated by one of said shift keys upon the release of said key to release the platen from its upper-case position.

16. A typewriting machine comprising a drive shaft, a worm thereon, a platen, a dog adapted to be moved by said worm, a rock shaft, a pinion thereon, a segment rack 80 engaging said pinion, means connecting said rack to said dog, means connecting the rock shaft to the platen to shift said platen to its upper-case position, and key-actuated means for moving the dog into engagement with 85 the worm.

17. A typewriting machine comprising a drive shaft, a worm thereon, a platen, a dog adapted to be moved by said worm, a rock shaft, a pinion thereon, a segment rack 90 engaging said pinion, means connecting said rack to said dog, means connecting the rock shaft to the platen to shift said platen to its upper-case position, key-actuated means for moving the dog into engagement with the 95 worm, a release pin carried by said rock shaft, a key, a release hook carried by said key and adapted to engage the release pin when said key is depressed and means adapted to be engaged by said hook when said key is released to disengage said hook from the release pin.

18. A typewriting machine comprising a drive shaft, a worm thereon, a platen, a dog adapted to be moved by said worm, a rock 105 shaft, a pinion thereon, a segment rack engaging said pinion, means connecting said rack to said dog, means connecting the rock shaft to the platen to shift said platen to its upper-case position, key-actuated means for moving the dog into engagement with the 110 worm, a stop pin carried by said shaft, and a rigid stop adapted to be engaged by said stop pin to lock the platen in its upper-case position.

19. In a case-shift mechanism, a shift frame, means for moving said shift frame from lower case position to upper case position, two independent sources of power normally disconnected from said shift-frame-moving means, a key, and means whereby when said key is depressed one of said sources of power is temporarily connected with said shift-frame moving means to move the frame to upper case position and the other source of power is temporarily connected with the frame-moving means to actuate said means in the reverse direction upon upward movement of the key.

20. In a case-shift mechanism, a shift

frame, means for moving said shift frame to upper case position and holding it there, two independent sources of power normally disconnected from said shift-frame-moving means, a pair of keys, means operable by depression of either key to temporarily connect one of said sources of power with said frame-moving means to move the frame to upper case position, and means operable by 10 only one of said keys to connect the other source of power with the frame-moving means temporarily during upward movement of said key to actuate the frame-moving means in the reverse direction.

15 21. A typewriting machine comprising a drive-shaft, a case-shift-support, mechanism interposed between the drive-shaft and the case-shift-support for shifting said support, a key, and means actuated by said key to 20 connect said support-shifting mechanism to the drive-shaft and maintain said connection during the entire shifting operation regardless of the movements of the key after the shifting action is begun.

25 22. A typewriting machine comprising a constantly-operating drive-shaft, a case-shift-support, mechanism for shifting said support normally disconnected from the drive-shaft, a key, and means actuated by 30 the key to engage and move a part of the support-shifting mechanism into connection with the drive-shaft and keep it in such engagement during the entire shifting operation without regard to subsequent movements of the key after the connection is established.

35 23. A typewriting machine comprising a constantly-operating drive-shaft, a support shiftable to change case, mechanism for 40 shifting the support normally disconnected from the drive-shaft, a key, means adapted to be actuated by said key to engage the support-shifting mechanism and connect it to the drive-shaft, and means to disconnect the support-shifting mechanism from the 45 drive-shaft at the completion of the case-shift movement.

50 24. A typewriting machine comprising a support shiftable to change case, mechanism for shifting the support, a constantly-rotating drive-shaft, key-operated means free from the support-shifting mechanism operable to temporarily engage the said mechanism and connect it to the drive-shaft, 55 means being also provided to disconnect the support-shifting mechanism from the drive-shaft at the completion of the case-shift movement and to cause said mechanism to be wholly disconnected from the key-operated means during the case-shift movement of the support.

60 25. A typewriting machine comprising a drive shaft, a case shift mechanism normally disconnected from said shaft and adapted to be operated through said shaft

for moving the case shift mechanism to its upper case position, two shift keys normally disconnected from the case shift mechanism, means adapted to be actuated by depression of either of said shift keys to temporarily 70 connect the case shift mechanism to the drive shaft for a predetermined period irrespective of the length of time the key is held depressed, means to automatically lock the case shift mechanism in its upper case position at the completion of the case shift movement, and means operated upon the release of one of the shift keys to release said lock and to permit the case shift mechanism to return to its normal lower case position. 75

80 26. A typewriting machine comprising a constantly operating drive shaft, a case shift mechanism normally disconnected from the drive shaft, two shift keys, means adapted to be actuated by each of said shift keys to set in motion case shift mechanism, means to automatically lock the case shift mechanism in its upper case position, means to automatically disconnect the case shift mechanism from the drive shaft at the completion of the case shift movement, and means actuated by the release of one of the case shift keys to unlock the case shift mechanism and permit it to return to its normal lower case position. 85

90 27. A typewriting machine comprising a drive shaft, a case shift mechanism normally disconnected from the said shaft, a case shift key normally disconnected from the case shift mechanism, means adapted to be actuated by depression of said key to connect the case-shift mechanism to the drive shaft, for a fixed period of time, means to automatically lock the case shift mechanism at the completion of the case shift movement, and means adapted to be operated upon the release of the case shift key to unlock the case shift mechanism and permit it to return to its normal position. 100

105 28. A typewriting machine comprising a constantly operating drive shaft, a worm thereon, a case shift mechanism adapted to be operated through said worm, key-actuated means for connecting said case shift mechanism to said worm, and means for automatically disconnecting the case shift mechanism from said worm upon the completion of the case shift movement. 110

120 29. A typewriting machine comprising a constantly operating drive shaft, a worm thereon, a case shift mechanism adapted to be operated through said worm, key-actuated means for connecting said case shift mechanism to said worm, means for automatically disconnecting the case shift mechanism from said worm upon the completion of the case shift movement, and means for locking the case shift mechanism in its upper case position. 125

130 30. A typewriting machine comprising a

drive shaft, a worm thereon, a dog adapted to be moved by said worm, a key, key-actuated means for moving said dog into engagement with said worm, and case shift mechanism adapted to be operated by said dog.

31. A typewriting machine comprising a constantly operating drive shaft, a platen, a case shift mechanism adapted to be operated through said shaft to move said platen to its upper case position and hold it there, two shift keys each adapted to independently connect the case shift means to the drive shaft without movement of the other key, and means actuated by one only of said two shift keys to release said case-shift mechanism and permit the platen to return to its normal position when the said shift key is released.

32. A typewriting machine comprising a constantly operating drive shaft, a platen, a case shift mechanism connected to said platen and adapted to be operated through said shaft, but normally disconnected therefrom, two shift keys normally disconnected from said case shift mechanism one of said keys actuating means to connect the case shift mechanism to the drive shaft, means to automatically lock the platen in its upper case position, and means operated by the other shift key and effective only upon upward movement of said key to cause a return movement of the platen to its normal position.

33. In a typewriting machine, a support shiftable to change case, mechanism for shifting the support, a continuously-driven shaft, a control-key in the keyboard of the machine, means operable by said key for connecting the shifting mechanism to said shaft so as to thereby power-shift the support, and means for maintaining said connection until the shifting is completed regardless of the position or movements of the control-key.

34. In a typewriting machine, a shiftable platen, mechanism for shifting the platen, a continuously-driven shaft, key-operated devices for connecting the shifting mechanism to said shaft so as to thereby power-shift the platen, and means for maintaining said connection until the shifting is completed regardless of the position or movements of the shift-key, means being provided in the shifting mechanism for locking the same when the shifting action is completed and means also being provided for automatically disengaging the shifting mechanism from the power-driven shaft when the shifting action is completed.

35. In a typewriting machine, power-driven means for case-shifting embodying a crank rock-shaft capable of alternately rocking in opposite directions, the power-means serving to rock it in one direction to make the case shift to the up-position, means

being provided for locking the parts in the up-position, and key-controlled devices for putting the power-means into action and also for releasing the lock-up means to permit a down-shift to take place, said power-driven means embodying a pair of toothed elements one affixed to the rock-shaft and the other to a reciprocating member in said power-driven means.

36. In a case-shift mechanism, a power-driven shift-frame actuating mechanism, a key, means whereby upon depression and release of said key said mechanism will always shift and hold the frame in upper case position, a second key, and means whereby said frame will be released, upon actuation of the second key following a case-shift operation effected by actuation of the first key, by a power movement of said frame-actuating mechanism initiated by the second key, said frame-actuating mechanism being moved both to shift the frame to upper case position and to effect release of the frame by power other than that applied to the keys by the operator.

37. In a typewriting machine, power-driven means for case-shifting, key-controlled devices for putting the power into action to thereby cause a case-shift action to take place through the medium of the power, and locking means, said key-controlled devices embodying a first key-lever having the function only of putting the power-devices into action and a second key-lever having the function not only of releasing the shifted mechanism when previously actuated by said first lever but also of putting the power-means into action, said shifting mechanism having a lost-motion connection between two of its elements to thereby permit an idle motion on the part of the shifting mechanism connected directly to the power when said second lever is operated merely for release purposes.

38. In a typewriting machine, power-driven means for case-shifting, key-controlled devices for putting the power into action to thereby cause a case-shift action to take place through the medium of the power, and locking means, said key-controlled devices embodying a first key-lever having the function only of putting the power-devices into action and a second key-lever having the function not only of releasing the shifted mechanism when previously actuated by said first lever but also of putting the power-means into action, said shifting mechanism embodying a pin-and-slot lost-motion connection between two of its elements to thereby permit an idle motion on the part of the shifting mechanism connected directly to the power when said second lever is operated merely for release purposes.

39. In a case shift mechanism, a shift frame, a frame-moving mechanism arranged

to shift the frame to upper case-position and hold it there, a source of power, a pair of keys each operating when depressed to render said source of power effective to actuate the frame moving means to shift the frame to upper-case position, a second source of power, and means adapted to be put into action by only one of said keys for rendering said second source of power effective to 10 actuate the frame-moving means to release the frame upon upward movement of the key following a depression thereof.

40. In a typewriting machine, a power-actuated case-shift mechanism embodying a 15 crank rock-shaft capable of alternately rock- ing in opposite directions and means for applying the power thereto on the up-shift, the mechanism being such that on said up- shift the crank will pass slightly beyond 20 center, means for stopping the crank in this position to thus hold the shift in the up- position, and key-controlled means for putting the power into action to cause said up- shift and also for turning the shaft back 25 beyond center to thus release the parts and permit the down-shift to take place.

41. In a typewriting machine, a power- actuated case-shift mechanism embodying a 30 crank rock-shaft and means for applying the power thereto on the up-shift, the mech- anism being such that on said up-shift the crank will pass slightly beyond center, means 35 for stopping the crank in this position to thus hold the shift in the up-position, and key-controlled means for putting the power 40 into action to cause said up-shift and also for turning the shaft back beyond center to thus release the parts and permit the down- shift to take place, said key-controlled means embodying a key-lever, spring-means for de- 45 pressing its inner-end and a spring-actuated hook carried by said lever for causing said beyond-center movement of the shaft.

42. In a key-controlled power-actuated 50 case-shift mechanism wherein a shift frame is moved between lower-case and upper-case positions by force other than that applied to the shift-key by an operator, the combination of means whereby the shifting power is automatically cut off and the shift frame 55 positively held against return movement in- dependently of the shifting power and power applied to the key when power-shifted to upper-case position and is automatically released by power and restored to normal 60 position when manual pressure on the shift- key is relieved.

43. In a key-controlled power-actuated

case-shift mechanism, wherein a shift-frame is moved between case-positions by force 60 other than that applied to keys by an operator, the combination of a shift-and-lock- up control key, a release-control key, means whereby the shift-frame is automatically restrained from returning to normal posi- 65 tion upon release of manual pressure on the shift-and-lock-up control key, and means whereby the shift-frame will be released, upon manual actuation of the release-con- trol key, by power other than that applied 70 to said release-control key by an operator, and will return to normal position only upon release of manual pressure applied by an operator to said release-control key.

44. In a typewriting machine, the com- 75 bination of a platen, a platen-support shift- able upwardly from lower-case position to an upper-case position, a source of power, means for shifting the platen-support nor- mally disconnected from the source of power, 80 a key for temporarily connecting the sup- port-shifting-means with the source of power, and means for maintaining said con- nection until the support reaches its upper- 85 case position and then breaking the con- nection irrespective of the position of the key, said support-shifting-means comprising parts shiftable relatively to each other by the source of power to positions in which they are held by the weight of the support 90 when the support reaches its upper-case position.

45. In a manually-controlled power-oper- 95 ated case-shift mechanism, the combination of a shift frame, means distinct from the power which moves the shift-frame to upper- case position for holding the shift-frame against return movement when shifted to upper case position, and key-controlled power means for effecting movement of the 100 shift frame to upper-case position and for subsequently releasing said shift frame, said key-controlled power means embodying man- ually operable keys, manual actuation of one 105 of which keys causes movement of the shift- frame to upper case position by power other than that applied to said key by an operator, and manual actuation of another of which keys causes a release operation of the shift- frame-holding means by power other than 110 that applied to the last-mentioned key by an operator.

This specification signed this August 27,
A. D. 1917.
